Specification for Design.

Patented July 12, 1921.

Application filed July 16, 1920. Serial No. 396,841. Term of patent 3½ years.

To all whom it may concern:

Be it known that I, WILLIAM PESHKIN, a citizen of the United States residing at the borough of Manhattan, city, county, and State of New York, have invented a new, original, and ornamental Design for Cases for Pencils, of which the following is a specification, reference being had to the accompanying drawing, forming part thereof.

character designated, showing my new design;

Fig. 2, is a front view showing the case in open position; and

Fig. 3, is a rear view of the same in open position.

I claim:

The ornamental design for a case for pencils, as shown.

WILLIAM PESHKIN.
